UNITED STATES PATENT OFFICE.

CHARLES J. NASH, OF CHICAGO, ILLINOIS, ASSIGNOR TO UNIVERSAL DRAFT GEAR ATTACHMENT CO., OF CHICAGO, ILLINOIS, A CORPORATION OF ILLINOIS.

YOKE FOR DRAFT-GEAR.

1,156,618.

Specification of Letters Patent. Patented Oct. 12, 1915.

Application filed April 28, 1913. Serial No. 764,101.

To all whom it may concern:

Be it known that I, CHARLES J. NASH, a citizen of the United States, and resident of Chicago, county of Cook, and State of Illinois, have invented certain new and useful Improvements in Yokes for Draft-Gears, of which the following is a specification, and which are illustrated in the accompanying drawings, forming a part thereof.

10 The invention relates to that type of yoke which comprises a strap for encircling the shock absorbing and transmitting elements, and a socketed head for engagement with the butt of the coupler bar. Its objects are 15 to secure simplicity of construction; improved means for retaining in working relation the strap and head when made as separate parts, and an improved filler for the rear end of the yoke.

20 The invention consists of a socketed head, a strap having its ends inserted through the head and folded outwardly and backwardly along the outer faces of the top and bottom walls of the head, and a filler block having 25 fingers which grip the rear end of the yoke.

In the accompanying drawings, Figure 1 is a plan view of the yoke; Fig. 2 is a side view thereof with some parts broken away; and Fig. 3 is a central longitudinal plan 30 section.

The head comprises a top wall 10, a bottom wall 11, and side wall 12. In the structure as shown the side walls are prolonged forwardly beyond the top and bottom walls, 35 and are provided with longitudinal key-receiving slots 13 to afford means for securing the head to the butt of a coupler bar (not shown) when the latter is inserted within its throat. The strap 14 of the yoke is preferably of wrought metal, and is given the usual U form to adapt it to inclose the cushioning and transmitting elements of the gear (not shown). The forward ends of the strap 14 are inserted loosely through the 40

45 head, and bear, respectively, against the inner faces of the top and bottom walls thereof 10 and 11, and are folded outwardly and backwardly, as shown at 15, 16, to overlap these walls and bear against their outer

50 faces. Preferably, though not necessarily, the yoke ends are thickened at the outward bend, as shown at 17, 18, to provide increased strength to resist pulling stresses.

When thus formed it becomes unnecessary to attach the strap to the head by rivets or other securing means. The head is free to slide upon the strap in the buffing action, and this sliding will occur if there be present any resistance to the backward movement of the strap. When the buffing stresses are relieved, the head will return to its normal position as represented in the drawings.

The hooks formed upon the forward ends of the side members of the yoke by turning them backwardly, as shown at 15, 16, resist any tendency of the yoke to collapse under excessive pulling stresses, and thus insure a proper engagement of the strap with the head at all times.

The yoke is shown as provided with a 70 filler block 19 at its inner end which forms a bearing for the rearward follower. The end 20 of the yoke may be symmetrically curved and the rear face of the block 19 is given a corresponding curvature. This 75 block 19 is of cast metal and may be hollow as shown and furthermore may, for the purpose of decreasing its weight, be perforated in its several walls as shown. The block is provided with a pair of integral fingers, 21, 80 22, located on its side walls and adjacent its rearward face and normally projecting diagonally outward as represented by dotted lines in Fig. 1. The outer end of each of these fingers is provided with an inturned 85 hook as represented at 23 and when the block is properly placed within the yoke end, the fingers are bent inwardly by a blow or by pressure, their hooks engaging the rearward face of the yoke end. By this 90 means the filler block is securely held in place and without the use of rivets or other securing means thereby avoiding the weakening of the yoke by perforations. The filler block is preferably a malleable casting in 95 order that its fingers may be properly flexed in assembling the parts.

I do not claim in this application the filler block 19 and the means for attaching it to the yoke, as this feature of my invention is 100 made the subject of an application which is a division of this one.

I claim as my invention,

1. In a draft gear yoke, in combination, a socketed head and a strap comprising side 105 members, the forward ends of which extend

through the head and are folded back along the outer faces of the walls thereof.

2. In a draft gear yoke, in combination, a socketed head and a U-shaped strap, the forward ends of the strap projecting through the head and being provided with hooks which receive the forward edges of the walls

of the head and have a bearing on the outer faces thereof in a direction perpendicular to the axis of the yoke.

CHARLES J. NASH.
